UNITED STATES PATENT OFFICE.

ALEXANDER KAISER, OF STOCKTON, CALIFORNIA.

DESIGN FOR A SOUVENIR SPOON.

SPECIFICATION forming part of Design No. 23,019, dated January 30, 1894.

Application filed January 2, 1894. Serial No. 495,453. Term of patent 3½ years.

To all whom it may concern.

Be it known that I, ALEXANDER KAISER, a citizen of the United States, residing at Stockton, in the county of San Joaquin and State of California, have invented and produced a new and original Design for Souvenir Spoons, of which the following is a full, clear, and exact specification, reference being had to the accompanying drawing, and to the letters of reference marked thereon, which form a part of this specification.

My invention relates to a new and original design for the handles and bowls of spoons, and consists in the configuration and ornamentation, as will be hereinafter described and claimed.

In the drawing: the figure is a front or obverse face of the spoon.

Referring by letter to the said drawing: F, o indicates the extremity or end of the handle which consists of a representation of the San Joaquin county building at the California Mid-Winter Exposition at San Francisco. Under this is the representation of a jet of flame 5 D, which rests above the representation of a gas well tower E, forming the continuation or narrow part of the handle, and extends up on either side of the lower wing of the building.

The lower portion of the handle and the upper portion of the bowl are provided with a 30 representation of a sheaf of wheat C, and where the handle is joined or connected to the bowl, is arranged a representation of a bow knot C'.

Beneath the sheaf of wheat and in the central portion of the bowl is a representation or front view of the San Joaquin county (California) court house; and beneath this representation is a space for any desired inscription. 35

The object of my invention is a spoon commemorative of the California Mid-Winter Exposition at San Francisco; and its essential features consist in its shape and ornamentation, as shown in the accompanying drawing. 45

Having described my design, what I claim is—

The design for a spoon as herein shown and described.

In testimony whereof I affix my signature in 50 presence of two witnesses.

ALEXANDER KAISER.
